CLAIM

The ornamental design for an accessory base, as shown and described.

DESCRIPTION

FIG. 1 is a front perspective view of the accessory base showing my design;

FIG. 2 is a rear perspective view of FIG. 1;

FIG. 3 is a right side elevation view of FIG. 1;

FIG. 4 is a left side elevation view of FIG. 1;

FIG. 5 is a top plan view of FIG. 1;

FIG. 6 is a bottom plan view of FIG. 1;

FIG. 7 is a front elevation view of FIG. 1; and,

FIG. 8. is a rear elevation view of FIG. 1.

The broken line disclosure represents portions of the accessory base that form no part of the claimed design.
